US00D497350S1

(12) United States Design Patent (10) Patent No.: **US D497,350 S**
Ichitsubo et al. (45) Date of Patent: **** Oct. 19, 2004**

(54) POWER AMPLIFIER MODULE

(75) Inventors: **Ikuroh Ichitsubo**, Kanagawa Prefecture (JP); **Guan-Wu Wang**, Palo Alto, CA (US); **Weiping Wang**, Palo Alto, CA (US)

(73) Assignee: **Micro Mobio Corp.**, Palo Alto, CA (US)

(**) Term: **14 Years**

(21) Appl. No.: **29/185,022**

(22) Filed: **Jun. 20, 2003**

Related U.S. Application Data

(60) Provisional application No. 60/397,261, filed on Jul. 19, 2002.

(57) CLAIM

The ornamental design for the power amplifier module, as shown and described.

DESCRIPTION

FIG. 1 is a top perspective view of a power amplifier module showing our new design;

FIG. 2 is a bottom perspective view thereof;

FIG. 3 is a bottom plan view thereof; and,

FIG. 4 is a bottom plan view of a modified embodiment of the design shown in FIGS. 1 through 3.

1 Claim, 2 Drawing Sheets

FIG. 1

FIG. 2

FIG. 3

FIG. 4
